UNITED STATES PATENT OFFICE.

CHARLES RAGNAR FREDSELL, OF NEWARK, NEW JERSEY.

MAGAZINE FOR LABELING MACHINES.

Application filed March 1, 1923. Serial No. 622,145.

To all whom it may concern:

Be it known that I, CHARLES RAGNAR FREDSELL, a citizen of the United States, residing in the city of Newark, county of Essex, and State of New Jersey, have invented a new and useful Improvement in Magazines for Labeling Machines, of which the following is a specification.

My invention relates to magazines used with labeling machines more particularly to the type of labeling machine in which the label magazine is moved to and from the article to be labeled and has for its object to provide a mechanism that will enlarge the contact surface of the label with the article upon it being presented to the article to be affixed.

Little or no trouble has been experienced in the design of a machine that will automatically label articles which present a flat surface to the reciprocating label magazine, but with a round or otherwise curved surface there has been insufficient contact surface to hold the label to the article with sufficient power to withdraw the label from the magazine and hold it until it is wiped in position. My magazine shapes up the label to conform to the curved surface to which it is to be affixed thereby presenting a larger contact surface between the label and the article which holds the label to the article until the wiping station completes the operation.

The foregoing and other features of my invention will now be described in connection with the accompanying drawings forming part of this specification in which I have represented my magazine in its preferred form, after which I shall point out more particularly in the claims those features which I believe to be new and of my own invention.

In the drawings:—

Figure 1 illustrates a plan view of my label magazine shown connected to a reciprocating labeling machine, and in relative position to an article to be labeled, and the pasting roller.

Figure 2 is an elevation of my magazine, as in Figure 1.

Figure 3 shows the magazine with relative position of the stack of labels as the foremost label first contacts with the curved surface on which it is to be affixed.

Figure 4 shows the magazine in further forward position with the label shaped up

conforming to the article on which it is to be affixed.

On the drawings the details of my improvement are illustrated in heavy lines, the broken lines illustrating a typical labeling machine mechanism in which the magazine is reciprocated to and from the article to be labeled.

The label applying mechanism includes a label box 1 or magazine mounted and operated in a manner peculiar to my invention for effecting the application of labels directly from the label box to the surfaces of the article or articles. Said label box is provided at its delivery end 2 with retainers in the form of lips 3, and said label box is mounted on a reciprocating member 4, such as a slide, positioned for movement in a path transversely to the line of feed of the articles upon the runway 5, it being preferred to detachably position the label box upon the slide and to interlock said box to the slide, whereby the label box may be dismounted at will and with facility and to be replaced with other label boxes in case it is desired to substitute other labels of a different size and character.

Within the label box is a follower 6, provided with a stem 7, the latter being retained in an operative relation to the label box by a cramping device so that the mass of labels are held or gripped between the follower 6 and the retainers 3 of the label box to such an extent that the foremost label of the mass will not be displaced out of position within said label box during the traversing movement of the paste roll 8 for applying the adhesive to the exposed surface of said foremost label. The label box and its contained parts are moved inward toward the runway by the motion of the label box slide, through any well known actuating means as rocker arm 9, and during this inward movement of said parts, the pasted label is pressed into contact with the surface of the article 10 so as to be affixed thereto. At this stage, the motion of the mass of labels with the follower 6 and the stem 7 is arrested by the resistance of the article, but the label box is capable of a continued bodily movement in the inward direction under the action of the actuating means 9, for the label box slide, the effect of which inward movement is to carry the retainers 3 of the label box inwardly beyond the foremost label, thus relieving the labels from the gripping action

obtained normally by the co-operation of the retainers 3 and the followers 6, whereby the foremost label is conformed to the contour of the curved surface of the article to be labeled by the spring shaping fingers 11 and pressed into intimate contact with the article. Upon the outward movement of the label box, the foremost label remains affixed to the article as it is free to slip out of the label box. The retainers of the label box re-engage with the next label in the mass and all the parts recede with the box 1 and the slide 4 so as to be withdrawn away from the path of the articles, the spring fingers 11 being withheld from the box by the stack of labels. Co-operating with the follower rod, or stem 7, is a cramping device by which a relative movement is obtained between the follower and the label box so as to compensate for the space vacated by the removal of the labels, as well as the looseness occasioned by the application of the label, said cramping device being in the form of a cramp plate 15 hung on the follower rod 7 held in vertical position by spring 16 when slide moves towards article to be labeled. On the outward movement of slide lower end of cramp plate 15 contacts with cushion spring 18 on guide rod 17 which has adjusting nuts for regulating the pressure of cushion spring. When spring 18 contacts with cramp plate it takes a slightly inclined position and binds on follower rod and brings the mass of labels firmly up against the label box retainers.

A paste roll 8 is shown associated with the label box for the purpose of applying an adhesive to the exposed face of the foremost label. Said paste roll 8 is mounted for traversing movement across the delivery end of the label box, and it is so guided or directed that said roll will contact with the surface of the label for practically the full width and length thereof, the roll being directed in a path which precludes the application of the adhesive to the edges of the labels confined within said box whereby the adhesive is so applied that the labels will not adhere one to the other, all of which is common to labeling machines which are provided with reciprocating magazines.

Most of the above description is common to labeling machines provided with reciprocating label magazines and requires no further description.

My invention is the means to conform the label to the shape of the article to be labeled and in carrying out my invention I employ the label box 1 mounted to reciprocate to and from a series of articles 10. In the magazine 1 is a stack of labels 20 held in between the follower 6 and the spring actuated yielding retaining lip 3. Spring shaping fingers 11 rest upon the stack of labels and are withheld by reason of the fact that the la-

bels are closely stacked between the follower and the retaining lips. As soon as the foremost label contacts with the article to be labeled and upon arresting of the movement of the follower 6 the continued movement of the magazine permits the spring shaping fingers 11 to enter between the labels on account of the looseness in the stack of labels and the foremost labels are conformed to the shape of the article to be labeled, as will be readily understood by referring to Figures 3 and 4. This presents a large gummed surface of the label to the article which provides a sufficient power to withdraw the label from the magazine as the movement of the magazine away from the article takes place.

Heretofore the retaining lips have been rigidly connected to the magazine and have been the cause of considerable trouble in their contacting with the article to be labeled in the event of the magazine travelling too close, thereby breaking or otherwise damaging the articles to be labeled. In my magazine the retaining lips 3 are telescopically mounted in the bottom and sides of the magazine. In the bottom of the magazine the retaining lips 3 slide in grooves provided for the purpose. On the sides I provide a somewhat different construction in which the lips 3 are fastened on the end of extensions 30 adapted to slide in bearings 31 held in extended position by the spring 32. This provides a quick release of the labels from frictional contact with the lips after compression for any cause and permits easy withdrawal of the foremost label when it is attached to the article to be labeled.

I am aware that labeling magazines have been used before on machines provided with reciprocating magazines such as that disclosed in United States Patent to C. S. Weeks, No. 1,425,351, patented August 8, 1922, but that machine and others now in use will not affix labels to curved surfaces and it is upon that detailed improvement I base my claims.

Having thus described my invention what I desire to secure by Letters Patent is:—

1. In a labeling machine, a label carrying magazine movable relatively to the path of articles to be labeled, shaping fingers normally held inoperable by the stack of labels, to conform the foremost labels to the contour of the curved surface of the article immediately upon the label coming in contact with the article.

2. In a labeling machine, a label magazine movable relatively to the path of articles to be labeled, shaping fingers normally held inoperable by the stack of labels, set in operation by the contact of the label with the article, to immediately conform the label to the convex shape of the article.

3. In a labeling machine, a label carry-

- ing magazine for directly applying a label to an article, means for moving said magazine relatively to the article, shaping fingers held inoperable by the compressed stack of labels to conform the label to the convex shape of the article upon the center of the foremost label contacting with the article.
4. In a labeling machine, a label carrying magazine mounted to move toward and from the article to be labeled, a follower in the magazine, means for arresting the movement of the follower, said arresting means being controlled by the movement of the magazine away from the article, means normally held inoperable by the stack of labels, to conform the label to the contour of the article upon arresting the movement of the follower.
5. In a labeling machine, a label carrying magazine open at the delivery end and provided with spring actuated label retaining means, means for imparting reciprocating motion to the magazine, a follower mounted within the magazine for co-operation with the label retaining means whereby the labels are confined interposed between the follower and the label retaining means, a friction device co-operating with the follower for permitting continued movement of the magazine and label retaining means toward the article, means normally held inoperable by the stack of labels, set in operation by the retarding of the follower to conform the label to the contour of the surface of the article upon continued movement of the magazine toward the article.
6. In a labeling machine, a label carrying magazine open at the delivery end and provided with longitudinally yielding label retaining lips, means to project the lips into their extended position whereby the frictional resistance between the lips and the foremost label is diminished as the label is withdrawn from the magazine.
7. In a labeling machine, a label carrying magazine movable relatively to the path of articles to be labeled; spring fingers mounted on the side of the label magazine held normally outside the magazine by the stack of labels when the label magazine is away from the article to be labeled, but enter the magazine when the foremost label contacts with the article to be labeled.
8. The device of claim 6 the yielding retaining means being spring actuated.
9. In a labeling machine, a label magazine open at the delivery end, provided with yielding retaining means and means normally held inoperable by the stack of labels, set in operation by the contact of the label with the article to be labeled to conform the label to the curvature of the article to be labeled.
10. In a labeling machine a label carrying magazine movable relatively to the path of articles to be labeled, label shaping fingers mounted on the side of the magazine held normally inoperative until the foremost label contacts with the article to be labeled, means to advance the stack of labels in the magazine to normally hold the shaping fingers in their inoperative position.
11. In a labeling machine, a label carrying magazine open at the delivery end and provided with yielding label retaining lips; spring fingers, mounted on the side of the magazine, held normally outside the magazine by the compressed stack of labels, but which enter the magazine when the foremost label contacts with the articles to be labeled to conform the foremost labels to the contour of the article to be labeled.
12. In a labeling machine, a reciprocating label carrying magazine adapted to move to and from the path of articles to be labeled, shaping fingers mounted on the sides of the magazine to conform the foremost labels to the contour of the curved surface of the article to be labeled immediately upon the foremost label coming in contact with the article to be labeled, means to advance the stack of labels in the magazine to normally hold inoperable the shaping fingers.

In testimony whereof I affix my signature in the presence of two witnesses.

CHARLES RAGNAR FREDSELL.
